(57) **CLAIM**

The ornamental design for an EV charger, as shown and described.

DESCRIPTION

FIG. 1 is a frontside view of an EV charger;
FIG. 2 is a backside view thereof;

FIG. 3 is a left side view thereof;

FIG. 4 is a right side view thereof;

FIG. 5 is a top plan view thereof;

FIG. 6 is a perspective view thereof;

FIG. 7 is another perspective view thereof;

FIG. 8 is another perspective view thereof; and,

FIG. 9 is another perspective view thereof.

The broken lines in the drawings depict portions of the EV charger that form no part of the claimed design.

1 Claim, 9 Drawing Sheets
